COLOR IMPROVEMENT OF PETROLEUM LUBRICATING OILS

Clinton H. Holder, Westfield, N.J., assignor to Esso Research and Engineering Company, a corporation of Delaware

No Drawing. Filed Jan. 2, 1957, Ser. No. 631,994

5 Claims. (Cl. 208—286)

This invention relates to an improved process for the finishing of petroleum lubricating oil base stocks especially with regard to upgrading and improving their color and stability. More particularly it relates to a process of this nature wherein the unfinished lube oil base stocks are first treated with aqueous alkali metal or alkaline earth hydroxides followed by hydrofining.

The treatment of petroleum lube base stocks with aqueous caustic or lime is well known at this time for the improvement of the quality thereof. The hydrofining of lubricating oils is also known, see e.g. Oil and Gas Journal, November 1, 1954.

These two treatments are considered alternative. They may be applied to raw (untreated) lube distillate fractions and achieve sufficient quality improvement (color, color stability, acid number reduction, etc.) to meet the specifications set down for finished lube base stock in certain of the less demanding applications. However, other lines of base stocks have specifications that cannot be met by a single, and rather inexpensive processing step. Heretofore it has been necessary to solvent extract such base stocks prior to hydrofining. By removing aromatic types the stock then becomes sufficiently responsive to hydrofining that the necessary quality improvement can be reached.

It has now been found that these petroleum lubricating oils can be upgraded, particularly with reference to color improvement, by treating them first with an aqueous metal hydroxide selected from the group consisting of hydroxides of alkali metals and alkaline earth metals, separating the oil from the treating medium by distillation whereby the oil is rerun in contact with the alkaline treating agent and hydrofining the rerun oil in the presence of a hydrofining catalyst. The results obtained are far superior to those resulting from the individual steps alone or from repeated utilization of each of the individual steps.

The petroleum lubricating oil base stocks treated are those known in the art. They may be distillates of any width falling within the boiling point range of about 625° to 1150° F. (equivalent atmospheric) or they may be higher boiling fractions recovered by deasphalting from residuum.

The material to be treated by this process can therefore represent any viscosity in the wide range of 35 up to 180 S.S.U. at 210° F. It applies most particularly to base stocks derived from the naphthenic base crudes such as Tia Juana, Coastal, Lagunillas, etc. It is not restricted to this class of crudes, however, since advantages are also derived by treating base stocks derived from paraffinic base crudes. Examples of particular lube base stocks which can be treated by this process are thus spindle oils, transformer oils, etc.

The oils are first treated with an aqueous hydroxide as mentioned previously. Because of cost considerations sodium hydroxide or lime (calcium oxide) are preferred. In general, lime is used in an amount of three to four times the theoretical to neutralize the acids con-

2

tained in the oil. About twice, or less, of the theoretical amount of sodium hydroxide is used. Likewise potassium hydroxide is more reactive than sodium hydroxide. The concentration of the hydroxide in water is not critical and lies in the range of about 10% to 60%. Generally, a 40° Baume strength caustic solution is used. If lime is used it is dumped as a powder into a tank containing water and equipped with a paddle to form a water-line slurry representing 10 parts lime and 90 parts water. This slurry is then pumped into the oil line going to the furnace ahead of the pipe still. Thus the oil is first contacted with the lime slurry at about 300° F. and passes through the furnace where steam is added and it is heated to a coil outlet temperature of around 700° F. at a pressure of about one atmosphere. The time of contact in the furnace above 600° F. conveniently is in the range of 30 to 120 sec.

The thus treated oil is then separated from the spent metal hydroxide solution by distillation under reduced pressure in a vacuum pipe still. The lubricating oil fraction is taken off usually as a sidestream of one or more fractions. The alkali or alkaline metal oxide is non-volatile and is in the small (generally 5% or less) bottoms fraction. The oil is thus rerun over the alkaline treating agent preparatory to the hydrofining treatment.

The separated oil after this treatment is then hydrofined in the conventional manner. For convenience the conditions are presented below.

Conditions in hydrofiner

	Broad Range	Preferred Range
Temperature, ° F.....	500-750	600-725
Pressure, p.s.i.g.....	100-1,500	400-800
Feed Rate, v./hr./v.....	0.25-5	0.5-3
H ₂ Treat, s.c.f./b.....	100-3,500	500-1,500
H ₂ Consumption, s.c.f./b.....	10-1,000	80-150

The hydrofining catalysts that can be employed in the hydrofining include 5-15% molybdena oxide on activated alumina, mixtures of cobalt oxides (2-6 wt. percent) and molybdenum oxides (6-15 wt. percent), an equivalent amount of cobalt molybdate on activated alumina, and other sulfur resistant hydrogenation catalysts such as those of the nickel, tungsten sulfide type.

Regeneration of the fixed bed catalyst may be required periodically, depending largely upon the nature of the feed stock. This regeneration is conveniently carried out at a temperature of about 750° to 1000° F. with an oxygen-containing gas.

In the hydrofining operation, the oil and hydrogen are contacted with catalyst by continuous flow through a vessel packed with catalyst. The oil feed to the reactor is preheated to the required temperature by means of a furnace or similar means. Hydrogen may or may not be heated prior to feeding to the reactor depending on the quantity used. The degree of contact of oil saturated with hydrogen with the catalyst is determined by the ratio of the oil flow rate to the catalyst volume.

After the hydrofining process has been carried out the liquid is then passed to a stripper to remove residual H₂S then it may be fractionated or kept intact.

The advantages of this invention will be better understood by reference to the following examples.

EXAMPLE

A light Tia Juana raw lube distillate having a viscosity of 10 to 105 S.S.U. at 100° F. (column I) was rerun over a lime-water slurry (8 parts lime and 92 parts water) representing four times the theoretical for neutralization of the organic acids. This was done in a batch laboratory distillation employing a vacuum of less than 1 mm. The bottoms yield was 4%. The rerun distillate

had inspections shown in column II. A portion of the latter was hydrofined over cobalt molybdate catalyst at 800 p.s.i.g., 800 s.c.f. hydrogen/b., a temperature of 650° F. and a feed rate of 1 v./v./hr. (column III). A second portion was hydrofined under the same conditions except the temperature was 575° F. (column IV). Another portion of the feed was hydrofined under the same conditions as column III but was not given any lime treatment (column V). Inspection data on these materials were as follows:

Hydrofining of Tia Juana lube distillate

Inspections	Raw	Rerun	Hydrofined		Hydro-
	Dist.	Dist.	Rerun Dist.	Raw Dist.	fined
	I	II	III	IV	V
Gravity, ° API.....	24.0	24.2	27.3	25.9	27.2

Pour Point, ° F.....	-45	-45	-35	-40	-40

¹ Color stability test—actual color after 16 hours at 212° F.

These data demonstrate that the lime treatment alone gave a product of only 9½ Tag Robinson whereas hydrofining alone gave a Tag Robinson number of 13. Only the combination of the two steps of this invention, columns III and IV, gave a Tag number of at least 18 or enough to satisfy specifications. Furthermore, the material produced at 650° F. and 1 v./v./hr. was shown to exhibit good color stability.

In other work it has been shown that spindle oils of this color can be made if the raw lube distillate is first extracted to a yield of about 80% before hydrofining. This is less desirable than the present process because the yields are reduced, extraction is more expensive than rerunning and solvent contamination in the extraction plant becomes a problem when such light stocks as this are extracted.

The advantages of this invention will be apparent to the skilled in the art. It can be used in either of two ways. Either, improved products of superior color characteristics are obtained in a simple, economical process, or, the use of the treatment with metal hydroxide before hydrofining permits of milder conditions for the latter.

This in turn yields products with less increase in pour point.

It is to be understood that this invention is not limited to the specific examples which have been offered merely as illustrations and that modifications may be made without departing from the spirit of the invention.

What is claimed is:

1. A process for upgrading and improving the color of a petroleum lubricating oil base stock which comprises the steps of treating the oil with a substantial excess of an aqueous metal hydroxide beyond that required for neutralization, said metal hydroxide being selected from the group consisting of hydroxides of alkali metals and alkaline earth metals at a temperature within the range of 300° to 700° F.; separating the thus treated oil from the aqueous metal hydroxide by distillation whereby the oil is rerun in direct contact with the alkaline treating agent and hydrofining the rerun oil in the presence of a hydrofining catalyst to produce an oil of improved color and in particular improved heat stability.

2. The process of claim 1 in which the metal hydroxide treating step is conducted above 600° F. for 30 to 120 seconds.

3. The process of claim 1 in which the hydrofining step is conducted at a temperature in the range of 500° to 750° F. and a pressure in the range of 100 to 1500 p.s.i.g.

4. The process of claim 3 in which the base stock has a viscosity of 35 to 180 S.S.U. at 210° F.

5. The method of bleaching a spindle oil which comprises treating the said oil with a substantial excess of a hydroxide beyond that required for neutralization, said hydroxide being selected from the class consisting of the aqueous hydroxides of alkali metals and alkaline earth metals at temperatures above 600° F., and feed rates of about 1 v./v./hr. and the duration of the treatment is from 30 to 120 seconds, separating the thus treated oil from the aqueous metal hydroxides by distillation whereby the oil is rerun in direct contact with the alkaline treating agent and hydrofining the oil in the presence of a hydrofining catalyst at temperatures within the range of 500°-700° F. and a pressure within the range of 100 to 1500 p.s.i.g.
